FARE BOX

Arthur T. Mitford and Frank O. Brickman,
Detroit, Mich.

Application December 28, 1936, Serial No. 117,782

40 Claims. (Cl. 232—15)

This invention relates to fare boxes or receptacles for the collection of fares such as coins, tickets, tokens or the like and particularly, although not necessarily, to boxes of this character which are adapted for use upon street-cars, railway cars, busses and other transportation vehicles.

A fare box embodying the present invention is preferably of the type in which the casing or cabinet proper is mounted upon a standard or upon the floor of a vehicle and adapted to remain in the vehicle. The fare box or cabinet contains a removable coin box or vault which is locked in place within the cabinet and can only be removed by a person or persons authorized to do so. The top or closure of the removable coin vault or box is preferably provided with a tiltable lid which serves as an inspection plate permitting the conductor or driver to inspect the coins or other medium of fare prior to their discharge into the coin receptacle or vault. When the removable coin receptacle is in place within the fare box cabinet its lid or inspection plate is supported beneath and adjacent an opening in the bottom of the depository unit or hopper of the fare box, which hopper is provided with a glass wall or walls so that the inspection plate is visible.

An object of the invention is to provide the fare box or cabinet and coin receptacle or vault with a removable handle member for operating the lid or inspection plate, said handle having the combined function of releasing locking means carried by the lid for locking the lid in closed position immediately the handle is partially or fully withdrawn from engagement with the coin receptacle.

Another object of the invention is to provide a construction in which the handle may be replaced after removal or partial removal from engagement with the coin receptacle cover which handle, when replaced, cannot be used to unlock the lid.

A further object of the invention is to provide a coin receptacle cover which cannot be unlocked after removal from the fare box except by a person having a key who must first unlock a door in a wall of said receptacle, reach into the box and manually release the locking means and then replace the operating handle to its operative position within the coin receptacle. Then and then only can the inspection plate or coin receptacle cover be opened.

A further object of the invention is to provide means which positively prevents the removal of the coin receptacle from the fare box while the

receptacle cover or inspection plate is in unlocked position or is in a partially open or tilted position.

Another object of the invention is to provide hinge means for the inspection plate which contains concealed means for positively locking the hinge against swinging movement except when the coin receptacle is in operative and locked position within the fare box.

Another object of the invention is to provide the inspection plate with concealed auxiliary locking means for maintaining it in closed and locked position even in the event of tampering with the main locking means for said plate.

Another object of the invention is to provide an inspection plate in which the locking means for the plate is positively sprung projected into locking position upon a partial or full withdrawal of the operating handle.

A further object of the invention is to provide means for concealing from view the locking mechanism carried by the inspection plate even though unauthorized access has been had to the interior of the coin receptacle.

A further object of the invention is to provide a fare box of the foregoing character with a hopper or depository unit having a coin chute therein provided with gravity actuated means to prevent the removal of coins from the depository upon inverting the fare box.

Another object of the invention is to provide an improved handle for operating the coin receptacle inspection plate with telltale means to indicate any unauthorized attempt to tilt the inspection plate when said plate is locked in closed position.

Another object of the invention is to provide releasable means for removably retaining the inspection plate operating handle in operative position.

The above and other objects of the invention will appear from the following description and appended claims when considered in connection with the accompanying drawings forming a part of this specification.

In said drawings:

Fig. 1 is a perspective view, partly broken away, of a complete fare box embodying the present invention.

Fig. 2 is a fragmentary vertical section taken substantially along the line 2—2 of Fig. 1.

Fig. 3 is a fragmentary vertical section taken substantially along the line 3—3 of Fig. 1.

Fig. 4 is a perspective view of a complete coin receptacle embodying the invention, said recep-

45

tacle having been removed from the fare box or housing.

Fig. 5 is a fragmentary side elevational view taken substantially along the line 5—5 of Fig. 2.

Fig. 6 is a horizontal section, on an enlarged scale, taken substantially along the line 6—6 of Fig. 2 looking in the direction of the arrows.

Fig. 7 is a longitudinal section taken substantially along the line 7—7 of Fig. 6 with the locking bolt for the inspection plate in unlocked position.

Fig. 8 is a view similar to Fig. 7 showing the locking bolt in projected or locking position.

Fig. 9 is a bottom perspective view of the inspection plate and cover or frame for the coin receptacle, showing the inspection plate in locked position.

Fig. 10 is a view similar to Fig. 9 showing the inspection plate unlocked and in partially open and tilted position.

Fig. 11 is a transverse vertical section taken substantially along the line 11—11 of Fig. 6, showing the handle in operative position and the inspection plate unlocked.

Fig. 12 is a view similar to Fig. 11, showing the operating handle partially removed with the locking bolt for the inspection plate in projected or locking position.

Fig. 13 is a view similar to Figs. 11 and 12 and illustrating the position of the parts with the handle removed and the inspection plate locking bolt in unlocked position.

Fig. 14 is a view similar to Figs. 11 to 13 inclusive, showing the operating handle replaced but in position ineffective to open the inspection plate.

Fig. 15 is a fragmentary vertical section taken substantially along the line 15—15 of Fig. 11, looking in the direction of the arrows and showing the handle shaft in operative position.

Fig. 16 is a fragmentary side elevation, partly in section, illustrating the first operation of inserting the handle.

Fig. 17 is a view similar to Fig. 16 illustrating the second position in the operation of inserting the handle.

Fig. 18 is a fragmentary vertical section taken substantially along the line 18—18 of Fig. 16.

Fig. 19 is a section taken substantially through the line 19—19 of Fig. 17.

Fig. 20 is a vertical fragmentary detail, partly in section, illustrating the position of the parts when the handle is partially withdrawn from engagement with the inspection plate locking bolt.

Fig. 21 is a fragmentary longitudinal vertical section, similar to Fig. 7, showing a modified form of inspection plate locking means.

Fig. 22 is a bottom plan view of the inspection and cover frame as shown in Fig. 21 and embodying a modified form of the invention.

Fig. 23 is a fragmentary transverse vertical section showing concealed positive locking means for the inspection plate pivot or hinge, with the parts in locked position.

Fig. 24 is a view similar to Fig. 23 showing the parts in unlocked position; and

Fig. 25 is a fragmentary vertical sectional view, on an enlarged scale, showing one form of safety device embodying the invention, taken substantially along the line 25—25 of Fig. 6.

Before explaining in detail the present invention it is to be understood that the invention is not limited in its application to the details of construction and arrangement of parts illustrated in the accompanying drawings, since the inven-

tion is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring particularly to the drawings, and especially to Figs. 1 to 4 inclusive thereof, there is shown a fare box embodying the present invention and a removable coin box or vault which is adapted to be supported within the fare box or casing and locked in place therein. In Fig. 1 the complete fare box is shown in which A represents the coin receptacle cabinet or casing of the fare box having a front door A' which is adapted to be locked in closed position by a lock A² of any conventional type such, for example, as a lock known in the art as a four-way lock. The cabinet comprises three solid metal walls 25 and a top secured to the walls and comprising a base plate 26 having a preferably rectangular opening 27 formed therein. The base 26 provides means for supporting a depository unit or hopper shown as a whole at B. The depository comprises, as shown, four upright angle corner braces 27a which support glass panels 28 providing the four transparent walls for the depository unit. As seen in Fig. 2 the base 26 is preferably secured to the fare box unit 25 by screws or the like 29 which pass through horizontal flanges 25a extending inwardly from the walls 25 and engage in the base 26. The base 26 is inwardly extended on three sides at 26a and each inward extension is provided with a depending flange 26b, these flanges defining the substantially rectangular opening 27.

The top of the depository unit is closed by a metal cap 30 having formed therein a coin or fare slot 31. Positioned within the depository and extending downwardly therein in zigzag formation is a coin chute shown as a whole at C. This chute includes a serrated top plate 32 supported by one wall of the metal cap and extending downwardly and inwardly at an angle so that its serrated lower edge 33 extends beyond the slot 31. The lower end of the coin chute is normally open when in upright position and is provided with one or a pair of pivotally mounted coin chute closure plates 34 and 35. These plates are pivoted at 34a and 35a respectively to the front and rear side walls of the lower section of the chute. These walls are provided with stop members 36 and 37 of strap-like formation which have their free ends projecting below the throat of the chute section and, as seen in Fig. 3, engage and provide stops or supports for the plates 34 and 35 and prevent them from being moved, by gravity, to open positions beyond that in which they are shown. As seen, these plates have serrated lower edges 34b and 35b, respectively. The purpose of the serrated pivoted plate or plates is to prevent the unauthorized removal or pilfering of coins by inverting the fare box. When the box or cabinet is inverted, the plates move about their pivots to closed positions, with the plate 35 overlapping the edge of the plate 34, thus closing the coin chute and preventing any coins which might be in the depository from being removed. The side walls, that is the wider walls 25, are provided adjacent their top edges or their inner faces with horizontally extending angle members 39 which have horizontal flanges projecting a short distance toward the center of the cabinet A. These angles or track members provide means

for supporting in suspended relation, a removable till or vault to be described below. The left wall 25 of the cabinet or housing A, see particularly Figs. 16 and 17, is provided with a circular opening to receive an operating handle hereinafter described. A pair of opposed horizontal slots 40a extend inwardly from the side edges of the opening and a third or angle slot 40b extends downwardly from said central opening, this slot, as shown, being arranged at an approximately 45° angle with relation to the horizontal slots 40a. A preferably rectangular plate 41 is applied to the wall 25, see Figs. 1, 2 and 5, and secured thereto in any suitable manner as by means of rivets 42. This plate is provided with a circular opening 43 which exposes the central opening in wall 25 and covers a portion of the outer ends of the slots 40a and 40b. A latch member 44 is pivotally mounted at 45 upon the plate 41 and is limited in its up and down movement by means of a slot 46 through which a stud 47 projects. The handle portion 44a of the latch is provided with a thumb piece 44b and the latch member is normally maintained in its down or approximately horizontal position as shown in Figs. 1, 2 and 5 by means of an expansion spring mounted upon the plate at 48 and having fingers or extensions 49 and 50 which engage, respectively, beneath the base 26 and the top edge of the latch 44. The latch member at the juncture of its depending finger portion and its main body portion is provided with a notch which is adapted to engage the shank of the operating handle to be hereinafter referred to.

Referring now particularly to Figs. 2 and 4, the removable coin receptacle or vault embodying the invention is shown as a whole at D. This vault comprises a bottom wall 51, side walls 52, a partial front wall 53 and a back wall 54. The front wall 53 has a loop-like handle member or bail 55 mounted thereon for the purpose of removing the coin receptacle and replacing it when the door A' of the fare box cabinet is unlocked and open. The lower face portion of the front end wall 53 of the coin receptacle is provided with a hinged door or closure 56 having a lock 57 of conventional construction so as to lock and seal the receptacle against access to its contents except by a duly authorized person. The top of the coin box or till D is closed by a cap member or cover which, as shown, is of rectangular shape to correspond to the cross sectional shape of the coin receptacle and comprises a frame having depending flanges which telescope over the upper edges or portions of the walls 25 of the coin receptacle. The frame member is preferably secured to the coin receptacle walls by means of bolts and nuts 58. The heads of the bolts are countersunk and the nuts are located within the receptacle as clearly shown in Fig. 2. When the removable coin receptacle D is located within the fare box cabinet it will be seen (Fig. 2) that the bottom edges of the side frame members of the cover portion of said receptacle or till rest upon the horizontal flanges of the tracks or angle members 39. Thus the removable coin receptacle, as shown, is suspended within the cabinet A and its top is supported adjacent the opening 21 formed in the base plate 26 of the depository unit and in register therewith.

As shown, see particularly Figs. 4, 9 and 10, the frame of the coin receptacle top or cover comprises depending side flanges 59, an inner or rear end flange 60 and a front flange 61 which, as shown, is centrally cut away or notched out at

62, these flanges all depending from the rectangular top frame portion 63. The top frame of the cover member supports a tiltable inspection plate 64 which is located within the opening surrounded by the top flange portions 63 and extends forwardly below the front section of the flange 63 and engages the under face thereof, see Figs. 7 and 8. The rear edge of the inspection plate 64 is flared upwardly at 65 so as to provide a substantially tight joint with the adjacent horizontal top flange portion 63. The swinging cover or inspection plate 64 is adapted to be supported in position by means of a hollow shaft or hinge member 66, this member being journaled in openings or bearings formed in the flanges 59 of the frame member and having its outer ends flush with the outer face of said flanges. One end of the tubular shaft 65 is provided with diametrically opposed slots or notches 67 which extend inwardly from the outer end of the shaft, as best seen in Figs. 11 to 14 inclusive.

The inspection plate 64 is secured to the tubular hinge member 66 by means of brackets or strap members 68 which in turn are attached to the under face of the plate by screws or the like 69. To prevent any relative rotation or movement between the plate and the hinge member, additional screws 70 are provided to attach the central portions of the brackets to the hinge member. Thus when the inspection plate is tilted from its horizontal or closed position of Fig. 9 to its partially open or tilted position of Fig. 10, the hinge member, supporting straps and plate move together as a unit. The under face of the inspection plate is provided with a pair of opposed laterally extending pins 71 and 72, these pins being fixed to the plate and having their free ends terminating adjacent the flanges 59 of the cover frame to serve as guides during the tilting movements of the plate 64. The plate 64 is maintained normally in closed position by means of a coiled spring 73 having one end 74 (see Fig. 6) engaging the under face of the frame 63 and its opposite end 75 engaging the guide pin 72.

As seen in Figs. 9 and 10, the under side of the frame 63 in the rear portion thereof is thickened to provide a depending block portion or projection 76. The under face of this projection is in substantially the same horizontal plane as that of the under face of the inspection plate 64 when said plate is in closed position. In accordance with the form of the invention shown in Figs. 9 and 10, a spring projected bolt or latch member 77 is mounted for longitudinal sliding movement on the under face of the inspection plate 64. The bolt, as shown, is rectangular in cross section and is provided at its forward end with a depending hand grip or finger piece 78. The bolt is also provided in its under face adjacent its lead end 79 with a pair of transverse notches or grooves 80 and 81, these grooves being slightly spaced apart and the groove 80 having a diameter somewhat greater than the diameter of the groove 81 for a purpose to be described hereinafter. The bolt 77 is mounted for sliding movement and guided in a substantially straight line path by means of a supporting bracket or strap 82 secured by screws or the like 83 to the inspection plate and extends through a transverse slot 70 formed approximately midway between the ends of the tubular hinge member 66. The lead end 79 of the bolt projects beyond the hinge member and when in projected position (Fig. 9), underlies the lug or fixed projection 76 to lock the in- 75

spection plate in closed position and thus prevent its tilting movement. The means for projecting the bolt into locked position, in the present instance, comprises a coiled tension spring or springs 85, one end thereof being secured at 86 to the tubular hinge member and the other end having its hook-like portion engaging a lug 87 on or adjacent the finger piece. Normally the spring 85 maintains the bolt in its projected or locking position, that is with its lead end 79 underlying the lug 76 on the fixed frame member. When projected, the larger notch 80 of the bolt is revealed but when retracted against the action of the spring 85, the smaller notch 81 is exposed, see Fig. 10. When in the retracted position of Fig. 10 the lead end 79 of the bolt has its end face disposed in approximately the vertical plane of the flared portion 65 of the inspection plate, see particularly Fig. 7, so that the inspection plate may be tilted into open position. A stop screw or bolt 88 is threaded into the inspection plate to prevent the retraction of the bolt 77 beyond a predetermined position, as seen in Fig. 7.

25 Referring particularly to Figs. 6, 9, 10 and 25, there is shown one form of safety device embodying the present invention which prevents removal of the coin receptacle or vault D from the fare box or casing A at all times except when 30 the inspection plate or cover 64 is in closed position. This is an important feature since if it were possible for an unauthorized person to gain access to the interior of the fare box casing A by opening the front door A', the coin receptacle 35 D could be pulled or forced out and its contents removed through the unlocked inspection plate if it were not for the safety means embodying the invention which prevents such removal of the coin receptacle except and only in the event 40 the inspection plate or lid thereof is closed and locked. For this purpose, and in accordance with the present disclosure, the rear edge of the inspection plate 64 at approximately the juncture of the plate proper and its flared end 65, and 45 preferably adjacent one corner of the plate at its under side, a block or hump of metal 89 is attached to or formed integral with the plate and projection below it. The frame 63 adjacent the wall or flange 60 is provided with a vertically 50 extending hole or aperture and, as shown, with a depending bored annular lug or boss 90. A preferably cylindrical housing or casing 91 having flanges 92 and a slot 93 in its front wall, houses a spring pressed pin or plug 94 which is 55 normally urged upwardly by a coiled spring 95. The pin 94 carries a projecting arm or member 96 which extends through the slot 93 and underlies the lug 89. When the plug 94 is in its operative or upwardly projected position (broken 60 lines, Fig. 25), it is located behind the depending inwardly spaced flange 25b of the fare box rear wall 25 so that any attempt to withdraw the removable coin receptacle D by grasping its handle 65 will be prevented so long as the inspection plate 64 of said receptacle is in tilted or open position. When, however, the inspection plate returns to its closed and locked position, the lug 89 depresses the finger 96 and moves the plug 94 downwardly against the action of the spring 95 to its full line position of Fig. 25, thus maintaining it out of engagement with the fare box cabinet or casing flange 25b.

70 The lock bolt or latch retaining and releasing mechanism and the removable operating handle

for swinging the inspection plate to open and/or closed position will now be described:

The lock bolt or latch 77 of the above described embodiment of the present invention, when released, is projected rearwardly or to the left of 5 Figs. 6 to 10 inclusive by means of the aforementioned tension spring 85 so as to position the lead end 79 of the latch bolt in locking position beneath and in engagement with the frame lug 76 (Figs. 8 and 9). As previously explained, the 10 bolt passes through a slot or notch in the tubular hinge member or housing 66 and is freely slidable therein.

The tube or housing 66 has a cylindrical bore 97 which, as shown, extends more than one-half the 15 length of the tube and has a diameter slightly smaller than the diameter of the bore 98 which extends through the remainder of the tubular hinge member. Located within the larger bore 98 and projecting into the adjacent portion of 20 the smaller bore 97 is a cylindrical plug or plunger member 100, provided with an enlarged head 101 having a preferably centrally disposed stud or projection 102. The tube 66 has an additional portion or bore 99 of greater diameter 25 than the bore portions 97 and 98. The bore 99 is preferably tapered and internally screw threaded to receive a removable threaded plug member 104 which may be pinned in place within the bore 99 to prevent tampering with the plug. 30 A compression spring 103 is positioned within the bore 98 and is centered at its inner end by engagement with the locating stud 102. The opposite end of the spring engages the inner face of the plug 104. Thus the tendency of the plug is 35 to remain normally projected inwardly under the action of the spring 103 when unobstructed by the bolt 77, in the position in which it is shown in Fig. 13. The plug 100 is prevented from being moved toward the left beyond its position of this 40 figure by engagement of the enlarged head 101 with a shoulder at the adjacent end of the bore 97.

The operating handle for engagement with and oscillation of the inspection plate 64 comprises, 45 as shown, a handle portion or finger piece 105, a shank portion 106 and an annular projection or ring-like stop 107. The diameter of the shank 106 is reduced at 108, the portions 106 and 108 being connected by a taper or bevel 109. The 50 lead or front end of the shank is further reduced and provides, as shown, an eccentric cylindrical end portion 110, this last named portion and the shank portion 108 being connected by a gradual taper or beveled portion 111. The end or face 55 of the lead portion 110 is preferably flat and in operation engages the adjacent preferably flat face of the plug or plunger 100, see Figs. 11 and 14.

The shank portion 106 adjacent the stop ring 107 is, as shown, provided with a pin having outwardly projecting diametrically opposed end portions 112 which, when the handle is in operative position with the inspection plate in its closed or horizontal position, project beyond opposite sides of the handle shank in a common substantially horizontal plane. The shank 106 is also provided with another pin 113 which extends downwardly from the shank when the handle is in normal operative position at an angle to the vertical and with relation to the position of the 60 aforementioned pin 112. This pin is located between the pin 112 and the stop ring 107 and serves as a stop for the handle when the shank thereof is inserted to its full operative position within the cylindrical hinge member 66, see Fig. 11. The 70 75

pin 112 is adapted to be brought into register with the corresponding slots 40a formed in the casing wall 25 and the stop pin 113 is adapted to be brought into register with the angle slot 40b formed in said casing wall 25 (Figs. 16 and 17) when the handle 105 is moved into a predetermined position at an angle to a vertical line passing through the fare box cabinet and corresponding to the angle of the slot 40b.

Referring now particularly to Figs. 6, 7, 10, 11 and 15, the inspection plate and its associated operating and locking mechanism are shown in normal unlocked operative position with the handle shank extending to its full depth within the tubular hinge or housing member 66. In this position the reduced end 110 of the shank is in engagement with the plug or plunger 100, the pin or pins 112 are located in the horizontal slots 67 in the sleeve 66 and the reduced portion 108 of the handle shank is projected through and located within the larger notch 80 formed in the latch bolt 71. In this position the plunger is held out of engagement with said notch and the handle is free to be actuated to tilt the inspection plate into an open position such as shown in Fig. 10, by moving the handle from its normal substantially vertical position of Figs. 1, 2 and 5 toward the right to its dotted line position of Fig. 17. The handle has been placed in this operative position with the inspection plate unlocked by first inserting the handle shank 106 into the bore 97, lifting the latch member 44 upwardly against the action of its spring 49, 50, alining the ends of the pin 112 with the slots 40a and pushing inwardly on the handle 105 until the angle pin 113 engages the wall 25, see Fig. 16. The handle 105 is now turned to the right until it assumes its dotted line position of Fig. 17 in which position the angle pin 113 is in register with the slot 40b. It may now be pushed inwardly until the pin 113 engages the end face of the tubular hinge member 66, see Fig. 11, the pin acting as a stop for the handle. The latch 44 is now released and the notch formed therein will engage the shank 106 between the thumb piece 105 and the stop ring 107 and releasably lock the handle in its operative position. The inspection plate can now be tilted at will by operating the handle 105. When it becomes desirable to lock the inspection plate in its closed position as in Figs. 9 and 12, the latch 44 is again released and the handle pulled straight outwardly. During this withdrawal movement of the handle the reduced shank portions 108 and 110 will be withdrawn from engagement in the bolt notch 80 whereupon the tension spring 85 immediately projects the bolt rearwardly or into its locked position as in Fig. 9. Upon withdrawal or partial withdrawal of the handle the compression spring 103 functions to force the plunger 100 forwardly into engagement with the adjacent face or wall of the lock bolt 71, see Fig. 12. With the bolt in locked position the smaller of the two notches 81 is located within and in substantial axial alinement with the bore 97 of the hinge member but since the diameter of the plug 100 is somewhat greater than the diameter of the notch 81, the plug cannot enter said notch but engages the surrounding portions of the face or wall of the bolt, thereby preventing it from locking the bolt in its projected position. When the parts 108 and 110 of the handle shank have been withdrawn from engagement with the bolt, the handle may be turned to aline the pin 113 with the slot 40b so that the shank can be farther withdrawn. Only an authorized person who has access to the

interior of the removable coin receptacle D through the door 57 may retract or withdraw the lock bolt from its locked position by grasping the finger piece 78 carried thereby. With the bolt in its retracted position as above described, the handle may again be pushed inwardly, whereupon the reduced portion 108 of its shank will enter the notch 81 and its end 110 will engage the adjacent face of the plunger 100. The plunger is thus pushed away from the bolt sufficiently to allow the handle shank to be moved into the sleeve 66 until it assumes its position of Fig. 14, with the stop pin 113 in engagement with the outer face of the casing wall 25. So long as the inspection plate 64 is maintained in locked position by the lock bolt, the handle cannot be turned from its normal upright position so as to aline the pin 113 with the angle slot 40b formed in the wall 25. In other words, once the handle shank is withdrawn from engagement with the larger bolt notch 80, thus permitting the spring 85 to project the bolt to its locking position, it is impossible to tilt the inspection plate even though the handle may be inserted into the smaller notch 81 and to its approximately full depth. Any attempt to tilt the inspection plate with the parts in their positions in Fig. 14 will cause the ends of the pin 112 to shear off due to the fact that the pin is made of softer metal than that of the shank and its engaging hinge member or tube. Such shearing off of the pin provides tangible evidence to the inspector, thus warning him that the fare box has been tampered with.

Referring particularly to Fig. 20, the relative positions of the parts of the inspection plate, operating handle shank and lock bolt are shown after the bevel 109 on the handle shank has been moved outwardly from engagement with the notch 80 during the initial part of the operation to release the bolt. By reason of the difference between the diameters of the reduced end portion 110 of the handle shank and that of the notch 80, the withdrawal of the shank portion 108 from the notch 80 permits the lock bolt 71 to move a short distance forwardly or toward its projected position, as shown in full lines in this figure, and thus prevents the spring pressed plunger 100 from again entering the notch 80 upon withdrawal of the shank which, if permitted, would again retain the bolt in its retracted position and permit the inspection plate to be swung into open position even though the handle shank had been fully withdrawn. As seen, by reason of the present structure and the differential of the cooperating parts, once the handle shank is even partially withdrawn, the bolt is immediately subjected to the direct action of the tension spring 85 which projects it into locked position as shown in Fig. 12. Once locked, the mechanism cannot be released to permit the tilting movement or opening of the inspection plate. This can be accomplished only by first gaining access to the interior of the removable coin receptacle D through its locked door 56, and then retracting the bolt manually through the medium of its handle or finger piece 78. When thus retracted, the larger notch 80 of the bolt is again brought substantially into axial alinement with the spring pressed plunger 100. The plunger is moved into engagement with said notch by its spring 103, the parts assuming the positions of Fig. 13. The handle shank may now be inserted in the manner above described with its reduced portion 108 located within the notch 80 and with its end 110 holding the plunger 100 in its ineffec-

tive or retracted position against the action of the compression spring 103.

Figs. 11 to 14 inclusive, illustrate the various positions of the parts during the above described operations. In Fig. 11 the handle is in its operative position ready to actuate the inspection plate. In Fig. 12 the handle has been partially withdrawn permitting the bolt to be projected by its spring or springs into locked position. Fig. 13 illustrates the position of the parts after an authorized inspector having access to the interior of the till D has withdrawn or retracted the bolt 77, and showing the spring pressed plunger 100 engaging the notch 80 to maintain the bolt in position to again receive the handle shank. Fig. 14 shows the positions of the parts with the handle shank portion 108 engaging the smaller notch 81 in the bolt, the bolt being in locked position.

Figs. 18 and 19 illustrate the positions of the parts during the initial step in the operation of inserting the operating handle when the inspection plate is closed and unlocked, Fig. 18 corresponding to Fig. 15 with the ends of pin 112 located in the slots 67 and with the pin 113 engaging the outer face of the cabinet wall 25. Fig. 19 illustrates the second step in the operation of inserting the handle shank 106 and shows the parts with the handle 105 having been moved to the right and in its dotted line position of Fig. 17. The stop or angle pin 113 is in register with the slot 40b in the wall 25. From this position, the handle shank may be moved inwardly until the stop pin 113 engages the end of the tubular hinge 66, as seen in Fig. 11. The second step involves tilting of the inspection plate. Upon release of the handle 105, the spring 73 returns the plate to closed position.

If desired, the under side of the inspection plate may be provided with a casing formed of sheet metal for the purpose of enclosing and concealing the latch bolt releasing and operating mechanism of the invention. As shown in Fig. 6, this casing preferably comprises a bottom wall or cover 114 having a slot or opening 115 formed therein through which the thumb or finger piece 78 projects. The casing is provided with side walls 116, one only being shown, a front end wall 117 and a rear end wall 118. The rear wall has a notch or cut-out portion through which the lead end 79 of the lock bolt projects. The cover may be secured to the inspection plate in any suitable and desirable manner. By thus enclosing the mechanism, even if a person did gain access to the interior of the coin receptacle, he would be unable to see the working parts of the cover or inspection plate operating and locking mechanism. Thus an additional safety feature is added to the coin receptacle.

Referring now particularly to Figs. 23 and 24, where desirable, auxiliary automatically operated means may be provided for locking the inspection plate in closed position. As shown, such means is adapted to cooperate with the hinge member of the removable coin receptacle to prevent rotation of the hinge member relative to its supporting frame.

As seen in these figures, the spring pressed plunger 100 has the usual enlargement or head portion 101 and an additional beveled portion 101a. The face of the bevel is engaged by one end of a compression spring 103, the other end of the spring engaging the inner face of the screw threaded plug 104 in the same manner as in the preceding forms. The frame portion 63 of the coin receptacle cover is preferably provided with

a recessed chamber or boss 119. A coil spring 120 is located in the recess and at one end engages a sliding non-rotatable key or plug 121 which in turn engages a second slidable but non-rotatable key member or plug 122. The second plug has a tapered face 123 which corresponds to the bevel or taper on the plunger portion 101a. The key member 122 is adapted to slide in an opening formed in the wall of the hinge 66, said opening having a cross sectional shape corresponding to that of the key 122. With the parts in the positions in which they are shown in Fig. 23, and with the reduced portion 108 of the operating handle located within the smaller diameter notch or groove 81 formed in the latch bolt 77, the slidable key or plug 122 has its tapered face in engagement with the bevel 101a and the key 121 has a portion which, in the present position of the parts, is located in the socket formed in the boss or member 119 and a portion extending into the opening formed in the hinge member wall. Thus it is impossible to rotate or oscillate the hinge member 66 relative to the frame 63. It will be understood that the lock bolt 77 is now in projected position and that the inspection plate cannot be opened while the bolt is thus projected for the reason that it is impossible to insert the shank of the handle member into the hinge beyond the point where it is shown in Fig. 23 since the pin or lug 113 carried by the shank is in contact with the outer face of the cabinet wall 25 and acts as a stop to prevent the full insertion of the handle shank to a point which would move the plunger 100 inwardly against the action of the spring 103. This would be necessary to shift the key members 121 and 122 into their releasing positions as shown in Fig. 24.

If the lock bolt 77 has been tampered with so as to prevent its full projection into locking position upon being released by withdrawing the handle shank and has moved only part way toward its locking position, the handle shank cannot be inserted to a sufficient depth in the hinge member to move the plunger 100 inwardly to release the keys 121 and 122 since, upon insertion of the shank, the end 110 thereof will engage that portion of the bolt which is located between and separates the notches 80 and 81, since such portion, with the lock bolt 77 in partially projected position registers with the bore 97 and serves as a stop for the handle shank. It will be seen, therefore, that so long as the lock bolt 77 is fully projected into locking position with the smaller notch 81 registering with the hinge member bore, the handle shank cannot be inserted far enough to release the plunger and key members. This is true also in the event the lock bolt 77 is only partially projected toward locking position.

In Fig. 24 the parts are shown in unlocked position. The bolt 77 has been manually retracted by engaging the finger piece 78. This cannot be done except by an authorized person who must first gain access to the interior of the cabinet, open the removable coin receptacle door and reach into the interior of said receptacle to grasp the finger piece carried by the bolt.

If the removable coin receptacle D has been withdrawn from its position within the cabinet A 70 and the bolt 77 is in projected or locking position, the insertion of the handle shank into the hinge member will have no effect upon the releasing of the bolt even though the spring pressed plunger 100 can be moved inwardly to release

the auxiliary inspection plate locking keys. If for any reason the bolt has been only partially projected prior to withdrawal of the coin receptacle from the cabinet, the handle shank can 5 not be inserted to a sufficient depth to release the plunger and locking keys. In this case the auxiliary locking keys 121 and 122 are effective to prevent tilting of the inspection plate into open position, thereby preventing access to the contents of 10 the receptacle.

With the parts as shown in Fig. 24, the shank of the operating handle has been inserted to its full depth to move the plunger 100 against the action of the spring 103 and thereby shift the 15 keys 121 and 122 into their non-locking positions. Upon withdrawal of the handle shank from engagement with the plunger, the spring 103 returns the parts to their position of Fig. 23.

In Figs. 21 and 22 there is shown a modified 20 form of inspection plate locking mechanism embodying the present invention. In the present form, the latch bolt for locking the inspection plate in closed position is projected forwardly, or to the right of Fig. 21, by means of a spring or 25 springs. The mechanism for retaining the lock bolt in its inoperative or unlocked position and for releasing it so that it can be projected into locked position is substantially the same as that described above.

30 The front portion 61 of the coin receptacle top or cover is provided with a recess 61a which is adapted to receive the lead end portion 79 of the lock bolt 77 when the same is in projected position. The bolt is supported against the under 35 side of the inspection plate by means of a combined strap member and guide 82 secured by screws 83 to the plate 64. The bolt passes through a transverse slot formed in the tubular hinge member or housing 66 in the same manner 40 as in the preceding form of the invention. An auxiliary bolt member or latch 125 is provided to operate independently of or in conjunction with the bolt 77 and, as seen in Fig. 22, this latch member is pivotally mounted at 126 to the under 45 side of the inspection plate and is normally maintained in its full line position by means of a tension spring 127. The side wall 59 of the receptacle top frame, as shown, is provided with an arcuate recess 59a and the wall 52 of the receptacle with a corresponding slot or opening 52a in 50 register with the recess. Thus when the swinging latch member or bolt 125 is moved from its full line position to its dotted line position, the outer end 125a thereof engages in the recess 59a thus preventing the inspection plate 64 from 55 being tilted even though the main bolt 77 is in retracted position. To effect this movement of the latch or bolt 125, there is provided an auxiliary 60 slidable plate or member 128 having notches 180 and 181 corresponding, respectively, to the notches 80 and 81 formed in the bolt 77. This 65 slidable plate rests flatwise against one face of the bolt 77 and is adapted to be guided in its reciprocal movement by the strap 82 and by the transverse slot formed in the hinge member 66. The side face of the plate 128 carries a laterally 70 projecting lug 129 which extends into the path of the inner end 125b of the auxiliary latch or bolt. The plate 128 is normally urged forwardly 75 or to the right of Figs. 21 and 22 by a tension spring 130 anchored at 131 to the under face of the inspection plate 64 and at the other end 132 to the slidable member 128. Thus as the shank of the handle 105 is withdrawn from its position 80 within the tubular member 66 it will successively

release the bolt 77 and the plate 128. Upon clearing bolt 77 the springs 85 will function to project the bolt forwardly until its lead end 79 engages in the notch 61a. As soon as the handle shank clears plate 128 the spring 130 functions 5 to move the plate 128 in the same direction causing the lug 129 thereon to move the auxiliary latch or bolt member 125 about its pivot against the action of the spring 127 and project it into the recess 59a in the side wall in the receptacle 10 frame. Since the movement of plate 128 is independent of the bolt 77 it will be apparent that the latch member 125 functions independently of bolt 77 to lock the inspection plate to the vault or coin box wall. Thus the inspection plate 64 15 upon the partial or complete withdrawal of the operating handle shank is operatively locked in two places. The plate or slide member 128 and the auxiliary latch 125 with their associated parts function to provide locking means which are 20 also independent of the main latch bolt 77 in the event the movement of said latch bolt into its keeper or recess 61a is prevented by unauthorized tampering with the bolt, such, for example, as by plugging the recess 61a to prevent the 25 entry of the bolt thereinto.

Inasmuch as the bolt 77 and the slideable and cooperating plate 128 are projected forwardly, these members are provided respectively with depending thumb pieces 77a and 128a, see Figs. 21 30 and 22, which are located side by side and are adapted to be engaged by the thumb or finger of the inspector so as to push both members inwardly simultaneously to unlock the cover 64.

From the foregoing it will be seen that we have 35 provided an improved fare box which is substantially proof against pilfering of the coins or other medium of fare and one in which the inspection plate carried by the removable coin receptacle is substantially locked in closed position 40 against tilting movement except when a duly authorized person has manually retracted the bolt from its projected position and when the operating handle shank is in its proper and operative position to tilt the inspection plate; also 45 one in which it is impossible to remove the coin receptacle or till from its position within the fare box cabinet or housing at any time except when the receptacle inspection plate or cover is in closed and locked position.

We claim:

1. A coin vault having a pivoted inspection plate, a lock bolt movable into locking position to lock the plate to the vault and into retracted position to permit pivotal movement of said plate, a plunger cooperable with the bolt to lock the same in retracted position, and an operating handle for said plate having a portion shiftable in one direction to move said plunger out of locking position and in another direction to permit movement of the bolt into locking position free of said plunger.

2. A coin vault having a pivoted inspection plate, a sliding lock bolt movable into locking position to lock the plate to the vault and into retracted position to permit pivotal movement of said plate, a plunger cooperable with the bolt to lock the same in retracted position, and an operating handle for said plate having a portion shiftable in one direction into the path of the bolt to move said plunger out of locking position and in another direction out of the path of the bolt to permit movement of the bolt into locking position free of said plunger.

3. A coin box having a pivoted inspection plate,

a sliding lock bolt movable into locking position to lock the plate to the box and into retracted position to permit pivotal movement of said plate, a plunger cooperable with the bolt to lock the same in retracted position, an operating handle for said plate having a portion shiftable in one direction to move said plunger out of locking position and in another direction to permit movement of the bolt into locking position free of said plunger, and means whereby said handle portion is shiftable into the path of the bolt when in locking and retracted positions.

4. A coin box for a fare box cabinet having a pivoted inspection plate, a lock bolt movable into locking position to lock the plate to the box and into retracted position to permit pivotal movement of said plate, means cooperable with the bolt to hold the same in retracted position, an operating handle for said plate having a portion shiftable in one direction to move said means out of bolt holding position and in another direction to permit movement of the bolt into locking position free of said plunger, and means for locking said box to the cabinet when the inspection plate is in open position.

5. A coin vault comprising a pivoted inspection plate, a latch bolt carried by said plate and shiftable across the pivotal axis thereof into and out of position to lock the plate to the vault, and an operating handle for the plate shiftable into the path of the bolt for holding the same retracted and shiftable out of the path of the bolt to permit movement thereof to locking position.

6. A coin vault comprising a pivoted inspection plate, a latch bolt carried by said plate and shiftable into and out of position to lock the plate to the vault, and an operating handle for tilting the inspection plate and shiftable in one direction into the path of the bolt to hold the same in retracted position and shiftable in the opposite direction out of the path of the bolt to permit movement thereof to locking position.

7. A coin vault comprising a pivoted inspection plate, a latch bolt carried by said plate and shiftable into and out of position to lock the plate to the vault, an operating handle for tilting the inspection plate and shiftable in one direction into the path of the bolt to hold the same in retracted position and shiftable in the opposite direction out of the path of the bolt to permit movement thereof to locking position, and spring means for shifting the bolt into locking position.

8. A removable coin receptacle for a fare box having a top provided with an opening, a pivoted inspection plate for closing said opening, a tubular hinge member for pivotally interconnecting the inspection plate and top, a lock bolt carried by the under face of the inspection plate and shiftable through said tubular hinge member, a spring pressed plunger located in the hinge member and engageable with said bolt to maintain the same in retracted position at a predetermined time, and an operating handle for tilting the inspection plate when the bolt is in said retracted position, said handle having a shank insertable through said tubular hinge and into contact with the plunger to move the same out of engagement with said bolt.

9. A removable coin receptacle for a fare box having a top provided with an opening, a pivoted inspection plate for closing said opening, a tubular hinge member for pivotally interconnecting the inspection plate and top, a lock bolt carried by the under face of the inspection plate and shiftable through said tubular hinge member, a

spring pressed plunger located in the hinge member and engageable with said bolt to maintain the same in retracted position at a predetermined time, an operating handle for tilting the inspection plate when the bolt is in said retracted position, said handle having a shank insertable through said tubular hinge and into contact with the plunger to move the same out of engagement with said bolt, and spring means for projecting said lock bolt into locking position upon withdrawal of said handle shank from engagement with said bolt.

10. A removable coin vault for a fare box having a top wall provided with an opening, a pivoted inspection plate for closing said opening, a tubular hinge member pivotally interconnecting the inspection plate and vault, a slideable locking bolt carried by the under face of the inspection plate and having its lead end projecting through a slot in the tubular hinge, said lock bolt having a notch formed therein adapted to register with said hinge member when the bolt is in retracted position, a spring pressed plunger located within the tubular hinge and having a restricted movement longitudinally therein, said plunger being adapted to engage the bolt notch when the bolt is retracted to maintain said bolt in its retracted position, an operating handle having a shank insertable in said tubular hinge member and through said bolt notch for tilting the inspection plate, said handle shank having a reduced end portion engageable with the plunger to move the latter out of engagement with said bolt notch, and spring means for projecting the bolt into locked position upon withdrawal of the handle shank from engagement with said bolt.

11. A removable coin vault for a fare box having a top wall provided with a substantially rectangular opening, a pivoted inspection plate for closing said opening, a tubular hinge member pivotally interconnecting the inspection plate and vault, a slideable locking bolt carried by the under face of the inspection plate and having its lead end projecting through a slot in the tubular hinge, said lock bolt having a notch formed therein adapted to register with said hinge member when the bolt is in retracted position, a spring pressed plunger located within the tubular hinge and having a restricted movement longitudinally therein, said plunger being adapted to engage the bolt notch when the bolt is retracted to maintain said bolt in its retracted position, an operating handle having a shank insertable through said tubular hinge member and through said bolt notch for tilting the inspection plate, said handle shank having a reduced end portion engageable with the plunger to move the latter out of engagement with said bolt notch, and spring means for projecting the bolt into locked position upon withdrawal of the handle shank from engagement with said bolt, said bolt having means accessible only from the interior of the coin receptacle for moving the bolt into retracted position when the handle shank is out of engagement with the notch in said bolt.

12. A removable coin vault for a fare box having a top wall provided with a substantially rectangular opening, a pivoted inspection plate for closing said opening, a tubular hinge member pivotally interconnecting the inspection plate and vault, a slideable locking bolt carried by the under face of the inspection plate and having its lead end projecting through a slot in the tubular hinge, said lock bolt having a pair of transverse notches adapted to successively register with the

5 tubular hinge member upon reciprocation of the bolt, a spring pressed plunger reciprocable in said hinge member and adapted to engage one of said notches to retain the bolt in retracted position, an operating handle for tilting the inspection plate and having a shank provided with a reduced end portion insertable through said tubular hinge member into engagement with either of said notches and said plunger whereby to move said plunger out of engagement with said bolt, and spring means for projecting the bolt into locked position upon withdrawal of the reduced end of the handle shank from engagement with the bolt notch and said plunger to release said bolt, said handle shank being capable of being reinserted within said hinge member and into engagement with the other notch in the bolt but incapable of tilting the inspection plate while the bolt is in projected locking position.

10 13. A removable coin receptacle for a fare box having a top provided with an opening, a pivoted inspection plate for closing said opening, a tubular hinge member for pivotally interconnecting the inspection plate and receptacle, a spring projected lock bolt carried by the under face of the inspection plate and slidable through a slot formed in said tubular hinge member, a spring pressed plunger located in the hinge member and engageable with said bolt to maintain the same in retracted position, an operating handle for tilting the inspection plate when the bolt is in said retracted position, said handle having a shank insertable through said tubular hinge and into contact with the plunger to move the same out of engagement with said bolt, and means cooperating with the tubular hinge member and plunger and operated by the plunger for preventing rotation of the hinge member regardless of the position of the lock bolt, said means being released only when the handle shank is in engagement with the bolt while said bolt is in its retracted unlocked position.

15 14. A removable coin receptacle for a fare box having a top provided with an opening, a pivoted inspection plate for closing said opening, a tubular hinge member for pivotally interconnecting the inspection plate and top, a lock bolt carried by the under face of the inspection plate and slidable through said tubular hinge member, a spring pressed plunger located in the hinge member and engageable with said bolt to maintain the same in retracted position at a predetermined time, an operating handle for tilting the inspection plate when the bolt is in said retracted position, said handle having a shank insertable through said tubular hinge and into contact with the plunger to move the same out of engagement with said bolt, and means carried by the lock bolt accessible only from the interior of the coin receptacle for manually retracting said bolt.

20 15. A removable coin receptacle for a fare box having a cover provided with an opening, a tilt-able inspection plate for closing said opening, a tubular hinge member for pivotally interconnecting the inspection plate and cover, a spring projected lock bolt carried by the under face of the inspection plate and slidable through a slot formed in said tubular hinge member, a spring pressed plunger located within the hinge member and engageable with said bolt at a predetermined time to maintain the bolt in retracted position, and an operating handle for tilting the inspection plate when the bolt is in said retracted position, said handle having a shank insertable through said tubular hinge and bolt and into

contact with the plunger to move the same out of engagement with said bolt.

16. A removable coin receptacle for a fare box having a top wall provided with a rectangular opening, a pivoted inspection plate for closing said opening, a tubular hinge member pivotally interconnecting the inspection plate and top wall and journaled in said wall, a slidable locking bolt carried by the inspection plate and having its lead end projecting through a slot in the tubular hinge, said lock bolt having a pair of transverse notches formed therein adapted to successively register with the tubular hinge member upon endwise movement of the bolt, a spring pressed plunger reciprocable in said hinge member and adapted to engage one of said notches to retain the bolt in retracted position, an operating handle for tilting the inspection plate and having a shank provided with a reduced end portion insertable through said tubular hinge member into engagement with either of said notches and said plunger whereby to move said plunger out of engagement with said bolt, and spring means for projecting the bolt into locked position upon withdrawal of the reduced end of the handle shank from engagement with one of the notches to release said bolt, said handle shank being capable of being reinserted within said hinge member and into engagement with the other notch in the bolt but incapable of tilting the inspection plate while the bolt is in projected locking position.

25 17. A removable coin receptacle for a fare box having a cover provided with an opening, a pivoted inspection plate for closing said opening, a tubular hinge member for pivotally interconnecting the inspection plate and cover, a spring projected lock bolt carried by the inspection plate and slidable through a slot formed in said tubular hinge member, a spring pressed plunger located within the hinge member and engageable with said bolt to maintain the same in retracted position at a predetermined time, an operating handle for tilting the inspection plate when the bolt is in said retracted position, said handle having a shank insertable through said tubular hinge and said bolt and into contact with the plunger to move the same out of engagement with said bolt, and means carried by the inspection plate for substantially concealing the hinge member and spring projected lock bolt.

30 18. In a fare box provided with a casing having a door in one wall thereof, a depository unit mounted upon the casing, a removable coin receptacle located within the casing and having a tilt-able inspection plate, a spring projected lock bolt for locking the inspection plate in closed position, a removable handle having a shank insertable through a wall of the casing and into engagement with the inspection plate for tilting said plate when the lock bolt is in retracted position, and means carried by the coin receptacle and engageable with a part on said fare box casing to prevent removal of the coin receptacle while the inspection plate is in open or unlocked position.

35 19. In a fare box provided with a casing having a door in one wall thereof, a depository unit mounted upon the top of the casing, a removable coin receptacle mounted within the casing and having a tilt-able inspection plate, a spring projected bolt for locking the inspection plate in closed position, a removable handle having a shank insertable through a wall of the casing and into engagement with the inspection plate for tilting said plate when the lock bolt is in retracted

position, and means carried by the coin receptacle and engageable with a part on said fare box casing to prevent removal of the coin receptacle while the inspection plate is in open position, said plate cooperating with said means when in closed position to render said means inoperative.

20. A fare box comprising a casing having a door, a depository unit mounted upon said casing, a removable coin receptacle located within the 10 casing and having a tilttable inspection plate, means carried by the coin receptacle and cooperating with a part on said casing to prevent removal of the coin receptacle when the inspection plate is in open position, and a removable handle for 15 tilting said inspection plate.

21. A fare box comprising a casing having a door, a depository unit mounted upon said casing, a removable coin receptacle located within the casing and having a tilttable inspection plate, and 20 spring projected means carried by said removable coin receptacle and engaging said casing to prevent withdrawal of the coin receptacle while the inspection plate is in open position, said inspection plate having a part movable into engagement 25 with said means to retract the same when the plate is in closed position to permit withdrawal of the coin receptacle from the fare box casing.

22. A fare box comprising a casing, a depository unit mounted upon the casing, a removable coin receptacle located within said casing, said coin receptacle having a tilttable inspection plate, a handle member for operating said plate and having a shank extending through an opening 30 in the casing and into engagement with the inspection plate, and a spring pressed latch member pivotally mounted upon an upright wall of the casing and engageable with said handle shank to releasably maintain said handle in operative position.

23. A fare box having in combination, a casing provided with a locked door in one wall thereof, a depository unit mounted upon said casing, a removable coin receptacle adapted to be supported within the casing, said coin receptacle having a top frame provided with an opening, an inspection plate for closing said opening, a tubular hinge member pivotally interconnecting the frame and inspection plate and journalled in the frame whereby said plate may be tilted into open or closed position, a spring projected bolt carried by the inspection plate for locking the same in closed position, said fare box casing having an opening in a wall thereof adapted to register with said tubular hinge member when the coin receptacle is in position within the casing, said wall having a pair of diametrically opposed horizontal slots extending outwardly from said opening and a third slot extending downwardly from the opening at an acute angle to said first mentioned slots, the end of said tubular hinge member having a pair of diametrically opposite notches formed therein adapted to register with the horizontal slots in said casing wall, and a handle having a shank insertable through said wall opening and into said tubular hinge member, said shank having a pin extending transversely therethrough adjacent the handle portion and a second pin projecting from the handle shank at an acute angle to the first named pin and interposed between the hand grip portion of the handle and said first named pin, whereby upon the initial insertion of the handle said first named pin passes through the horizontally disposed slots in the cas-

ing wall and into the diametrically opposed notches in the tubular hinge member to permit the inspection plate to be tilted to open position to bring the second named pin on the shank into register with the acute angle slot in the casing 5 wall to permit the handle shank to be moved into its full operative position within the hinge member until the second pin engages the end face of the hinge member to prevent further insertion of the handle shank.

24. A removable till for a fare box having a cover provided with an opening, a tilttable inspection plate carried by the cover for closing said opening, a tubular hinge member attached to said inspection plate and journalled at opposite 10 ends in said cover, said hinge member having a transverse slot extending therethrough, a spring projected lock bolt slidably mounted upon the under side of said inspection plate and extending through said transverse slot, said bolt 15 having transverse notches formed therein adapted to register with said tubular hinge member at predetermined times, a tension spring connected to said bolt and to said inspection plate for normally projecting the bolt into engagement with 20 said cover to lock the inspection plate in closed position, a slideable bar located at one side of said bolt and projecting through the transverse slot in said hinge member, said bar having transverse 25 notches corresponding to and normally register- 30 ing with the notches in said lock bolt, a lug carried by said bar, a tension spring for normally projecting the bar in the direction of projection of the lock bolt, a pivoted latch member carried by said inspection plate and normally maintained in inoperative position, one end of said 35 latch projecting into the path of and being engaged by said lug, and an operating handle having a shank extending into said tubular hinge member and through a pair of said notches for 40 tilting the inspection plate when the lock bolt is in retracted position, said lock bolt and latch being projected into engagement with said cover at different points to lock the inspection plate in 45 closed position upon withdrawal of said handle shank from engagement with said pair of notches.

25. A removable till for a fare box having a cover provided with an opening, a tilttable inspection plate carried by the cover for closing 50 said opening, a tubular hinge member carried by said inspection plate and journalled at opposite ends in said cover, said hinge member having a transverse slot extending therethrough, a slideable lock bolt carried by the under face of said 55 plate extending through said slot and adapted to be moved into and out of engagement with a portion of said cover, a slideable bar engaging and extending along one face of said lock bolt and projecting through said transverse slot, said lock 60 bolt and said bar having registering pairs of transverse notches formed therein, one pair of notches being of smaller diameter than the other pair of notches, said bar having a lug on the outer face thereof, a latch member pivotally 65 mounted upon the under side of said inspection plate and having an end normally positioned in the path of and in contact with said lug, the other end of said latch member being adapted to be positively moved into engagement with a 70 portion of said cover, a tension spring for maintaining said latch member normally out of engagement with said cover, an operating handle having a shank extending into said tubular hinge member and through the larger pair of notches 75

for tilting the inspection plate when the bolt and bar are in retracted position, and independent spring means for projecting the bolt and latch member into engagement with different portions of said cover upon withdrawal of the handle shank from engagement with said pair of larger notches.

26. A removable till for a fare box having a cover provided with an opening, a tiltable inspection plate carried by the cover for closing said opening, a tubular hinge member carried by said inspection plate and journaled at opposite ends in said cover, said hinge member having a transverse slot extending therethrough, a slideable lock bolt carried by the under face of said plate extending through said slot and adapted to be moved into and out of engagement with a portion of said cover, a slideable bar engaging and extending along one face of said lock bolt and projecting through said transverse slot, said lock bolt and said bar having registering pairs of transverse notches formed therein, one pair of notches being of smaller diameter than the other pair of notches, said bar having a lug on the outer face thereof, a latch member pivotally mounted upon the under side of said inspection plate and having an end normally positioned in the path of and in contact with said lug, the other end of said latch member being adapted to be positively moved into engagement with a portion of said cover, a tension spring for maintaining said latch member normally out of engagement with said cover, an operating handle having a shank extending into said tubular hinge member and through the larger pair of notches for tilting the inspection plate when the bolt and bar are in retracted position, independent spring means for projecting the bolt and latch member into engagement with different portions of said cover upon withdrawal of the handle shank from engagement with said pair of larger notches, and a spring pressed plunger located within the tubular hinge member and having a portion engaging the said larger pair of notches to maintain said bolt and bar in retracted position at predetermined times.

27. A removable till for a fare box having a cover provided with an opening, a tiltable inspection plate carried by the cover for closing said opening, a tubular hinge member carried by said inspection plate and journaled at opposite ends in said cover, said hinge member having a transverse slot extending therethrough, a slideable lock bolt carried by the under face of said plate extending through said slot and adapted to be moved into and out of engagement with a portion of said cover, a slideable bar engaging and extending along one face of said lock bolt and projecting through said transverse slot, said lock bolt and said bar having registering pairs of transverse notches formed therein, one pair of notches being of smaller diameter than the other pair of notches, said bar having a lug on the outer face thereof, a latch member pivotally mounted upon the under side of said inspection plate and having an end normally positioned in the path of and in contact with said lug, the other end of said latch member being adapted to be positively moved into engagement with a portion of said cover, a tension spring for maintaining said latch member normally out of engagement with said cover, an operating handle having a shank extending into said tubular hinge member and through the larger pair of notches for tilting the inspection plate when the

bolt and bar are in retracted position, and independent spring means for projecting the bolt and latch member into engagement with different portions of said cover upon withdrawal of the handle shank from engagement with said pair of larger notches, said smaller pair of notches being adapted to receive the handle shank upon its reinsertion into the hinge member.

28. A removable vault for a fare box having a cover provided with an opening, a tiltable inspection plate carried by the cover for closing said opening, a tubular hinge member secured to said inspection plate and journaled at opposite ends in said cover, said hinge member having a transverse slot extending therethrough, a slideable lock bolt carried by the under face of said plate extending through said slot and adapted to be moved into and out of engagement with a portion of said cover, a bar extending along one face of said lock bolt and projecting through said transverse slot, said lock bolt and said bar having registering pairs of transverse notches formed therein, one pair of notches being of smaller diameter than the other pair of notches, a lateral projection on said bar, a latch member pivotally mounted upon the under side of said inspection plate having its inner end normally positioned in the path of and in contact with said projection, the outer end of said latch member being adapted to be positively moved into engagement with a portion of said cover, a tension spring for maintaining said latch member normally out of engagement with said cover, an operating handle having a shank extending into said tubular hinge member and through the larger pair of notches for tilting the inspection plate when the bolt and bar are in retracted position, and separate spring means for projecting the bolt and latch member into engagement with different portions of said cover upon withdrawal of the handle shank from engagement with said pair of notches, said handle shank being capable of being reinserted to engage the pair of smaller notches but incapable of tilting the inspection plate into open position while so engaged.

29. A removable coin receptacle for a fare box having a cover provided with an opening, a tiltable inspection plate carried by the cover for closing said opening, a tubular hinge member secured to said inspection plate and journaled at opposite ends in said cover, said hinge member having a transverse slot extending therethrough, a spring projected lock bolt slidably mounted upon the under side of said inspection plate and extending through said transverse slot, said bolt having transverse notches formed therein adapted to register with said tubular hinge member at predetermined times, a tension spring connected to said bolt and to said inspection plate for normally projecting the bolt into engagement with said cover to lock the plate in closed position when the handle shank is withdrawn, and auxiliary locking means for the inspection plate cooperating with said bolt but operable independently thereof upon withdrawal of said handle shank to engage said receptacle cover.

30. A removable coin vault for a fare box cabinet, comprising a pivoted inspection plate, a plurality of latch members movable into positions transverse one to another to lock the inspection plate to the vault, means for holding said latch members in retracted non-locking positions, and an operating handle for said inspection plate having means shiftable to release said holding

means and also to permit independent operation of said latch members.

31. A removable coin vault for a fare box cabinet, comprising a pivoted inspection plate, a plurality of latch members movable into positions transverse one to another to lock the inspection plate to the vault, and an operating handle for said inspection plate having a portion shiftable in one direction to successively release said latch members.

32. A removable coin vault for a fare box cabinet, comprising a pivoted inspection plate, a plurality of latch members movable into positions transverse one to another to lock the inspection plate to the vault, an operating handle for said inspection plate having a portion shiftable in one direction to successively release said latch members, and spring means for independently shifting said latch members into locking positions.

33. A fare box comprising a cabinet, a removable coin vault mounted in said cabinet and having an opening and a tiltable inspection plate for closing the opening, a handle cooperable with the inspection plate for tilting the same, and spring projected means having a part engaging the plate when in closed condition and releasable upon tilting said plate for locking the vault to the cabinet.

34. A fare box comprising a cabinet, a removable coin vault mounted in said cabinet and having an opening and a tiltable inspection plate for closing the opening, a handle cooperable with the inspection plate for tilting the same, and a latch member spring pressed into position to lock the vault against removal from the cabinet when the inspection plate is tilted, said latch member being moved out of locking position by the inspection plate when the inspection plate is disposed in position to close said opening.

35. A fare box having a movable inspection plate, a plurality of latch bolts for locking the plate to different sides of the box, and a removable handle for opening and closing the inspection plate and movable in one direction to hold

the latch bolts in retracted positions and in the opposite direction to release said bolts.

36. A fare box having a movable inspection plate, a plurality of spring actuated latch bolts for locking the plate to different sides of the box, and a removable handle for opening and closing the inspection plate and movable in one direction to hold the latch bolts in retracted positions and in the opposite direction to release said bolts.

37. A fare box having a pivoted inspection plate, a handle having a shank mounted at the pivotal axis of the plate, a latch bolt shiftable across said axis to lock or unlock the plate with respect to the box, said handle shank being shiftable in one direction to hold the bolt retracted and in the opposite direction to release the bolt, and spring means for moving the bolt to locking position.

38. A fare box having a movable inspection plate, a plurality of latch bolts for locking the plate to the box, and a removable handle for opening and closing the inspection plate and movable in one direction to hold the latch bolts in retracted positions and in the opposite direction to release said bolts.

39. A fare box having a movable inspection plate, a plurality of spring actuated latch bolts for locking the plate to the box, and a removable handle for opening and closing the inspection plate and movable in one direction to hold the latch bolts in retracted positions and in the opposite direction to release said bolts.

40. A fare box comprising a cabinet, a removable coin vault mounted in said cabinet and having an opening and a tiltable inspection plate for closing the opening, a handle cooperable with the inspection plate for tilting the same, and normally retracted stop means carried by said vault and adapted to be projected into engagement with a part of said cabinet for locking the vault against removal from the cabinet when the inspection plate is tilted.
